US0D1033492S

(12) **United States Design Patent** (10) **Patent No.:** **US D1,033,492 S**
(45) **Date of Patent:** **** Jul. 2, 2024**

(54) **REFRIGERATOR**

(71) Applicant: **Electrolux Home Products, Inc.**,
Charlotte, NC (US)

(72) Inventors: **Luis Fernando Zeni Filho**, Curitiba
(BR); **Gabriel Lied**, Curitiba (BR);
Charles David Baker, Charlotte, NC
(US); **Brent Curtis**, Terrell, NC (US);
Benjamin Shrader, Charlotte, NC
(US); **Josh Hanson**, Huntersville, NC
(US); **Cristhian Camacho**, Charlotte,
NC (US); **Swaminathan Iyer**, Galaxis
(SG); **Ola Lantz**, Galaxis (SG); **Eunice
Cheng**, Galaxis (SG)

(73) Assignee: **Electrolux Home Products, Inc.**,
Charlotte, NC (US)

(**) Term: **15 Years**

(21) Appl. No.: **29/751,197**

(22) Filed: **Sep. 18, 2020**

Related U.S. Application Data

(62) Division of application No. 29/661,621, filed on Aug.
29, 2018, now Pat. No. Des. 909,435.

(30) **Foreign Application Priority Data**

(57) **CLAIM**

The ornamental design for a refrigerator, as shown and described.

DESCRIPTION

FIG. 1 is a front perspective view of a refrigerator showing our new design;
FIG. 2 is a front view thereof;
FIG. 3 is a left side view thereof;
FIG. 4 is a right side view thereof;
FIG. 5 is a top view thereof;
FIG. 6 is a front perspective view of a second embodiment of a refrigerator;
FIG. 7 is a front view thereof;
FIG. 8 is a left side view thereof;

FIG. 9 is a right side view thereof;
FIG. 10 is a top view thereof;
FIG. 11 is a front perspective view of a third embodiment of a refrigerator;
FIG. 12 is a front view thereof;
FIG. 13 is a left side view thereof;
FIG. 14 is a right side view thereof;
FIG. 15 is a top view thereof;
FIG. 16 is a front perspective view of a fourth embodiment of a refrigerator;
FIG. 17 is a front view thereof;
FIG. 18 is a left side view thereof;
